CAN COOKER

Pierre Carvallo, Barcelona, Spain

Application August 3, 1946, Serial No. 688,226
In France August 20, 1945

11 Claims. (Cl. 99—361)

1

In a prior patent, I have described and claimed, in connection with the art of continuously sterilizing or pasteurizing food product containers, the use of baskets made of perforate metal sheets or of equivalent construction forming the treating unit and which are automatically fed through the apparatus and into which may be introduced containers of any shape and type for the purpose of treating the latter.

The present invention provides improvements relating to the construction of the means for circulating or feeding such baskets and to the method of introducing containers into and extracting same from said baskets.

One object of the invention is to provide a runway or path of travel for said baskets in the form of an endless circuit wherein no handling of the baskets is required at any point, a mechanical device being adapted to immobilize said baskets during filling and extracting operations.

Another object of the invention is to provide an automatic means for discharging treated containers from said baskets and also for charging into said baskets containers to be treated, said means being in the form of a ramming piston controlled by a chain device or a pneumatic tube or equivalent means adjusted in timed relationship with the travelling of said baskets.

A further object of the invention is to provide, in connection with the treatment of metallic cans the bottoms of which are liable to be puffed, or to expand, during the treatment, a safety device preventing the introducing into said baskets of an excessive number of cans.

Another object is to provide, more particularly in connection with the treatment of glass or similar fragile containers, liable to breakage in the course of treatment, means for extracting said containers from said baskets in the form of a scoop or trough adapted to be first introduced into said baskets under said containers, then to drive said containers out of said baskets thereby avoiding any risk of jamming said containers due to the possible presence of fragments of broken containers in said baskets.

A further object of the invention is to provide, in an apparatus of the type described, for carrying out a treatment at high temperatures and pressures, a circulating path for said baskets comprising a head of water serving as a water seal and making it possible to introduce and remove said baskets into and from an enclosure under pressure, wherein the temperature of treatment may be adjusted with a high degree of accuracy by adjusting said head of water.

2

A further object is to provide an apparatus of the type described more particularly designed for the treatment of fragile containers, wherein said baskets are successively fed through a plurality of tanks containing water at temperatures in stepped relationship, said tanks being concurrently used both for increasing and reducing the temperature of said containers, thereby ensuring substantial compensation between the heat calories used for heating and cooling said containers.

Further objects and advantages of the invention will be pointed out as the description proceeds in reference to the accompanying drawings given by way of example only, of several operative embodiments of the invention.

In the drawings:

Fig. 1 is a diagrammatical sketch of an example of an endless circuit for the circulation of baskets through various treating tanks.

Fig. 2 diagrammatically illustrates in elevation a treating apparatus enabling, through the use of feed selecting devices, a rapid speed of rotation of the baskets.

Fig. 3 is a fragmentary plan view of Fig. 2.

Fig. 4 is a diagrammatic section on line IV—IV of Fig. 2.

Figs. 5, 6 and 7 illustrate, at enlarged scale, one basket associated with the conveyor chains provided with pushing fingers and with runways.

Fig. 8 shows, at enlarged scale, the filling and ejecting stations.

Fig. 9 is a diagrammatic illustration in cross-section of an apparatus specially designed for treatment in steam under pressure.

Fig. 10 diagrammatically illustrates in section an apparatus designed for treatment in hot water under pressure, enabling operation under an over-pressure.

Fig. 11 diagrammatically illustrates in section an apparatus designed for the treatment of containers made of glass or other brittle material and for example for the pasteurizing of bottled beer.

Figs. 12 to 14 respectively illustrate in elevational, plan and side view, an automatic chain-controlled plunger for extraction providing if required for the upsetting of the ramming arm at the end of its stroke.

Fig. 15 shows in elevational section a plunger acting for the filling of the basket.

Figs. 16 and 17 show a plunger provided with a scoop or trough.

In Fig. 1, an endless circulating circuit for the baskets 23 is constituted by a pair of parallel run-

ways 3 the spacing of which corresponds to the length of the baskets, and which successively pass through various tanks 20, 21 and 22 containing the heat treating fluids. Along each path 3, an endless chain 2 provided with driving fingers 1 ensures the travelling of baskets 23 on runways 3. At some point in the circuit, such as A, the containers to be treated are introduced into the baskets 23 at B, the treated containers are extracted therefrom, the direction of travelling of the baskets 23 being indicated by the arrow f.

Said baskets 23 are, for example, constituted by a perforated metal sheet 80 and are preferably mounted on two annular end members 81 so as to be able to roll on the guide- or runways 3 (Figs. 5 to 7). Said baskets may have any desired shape in cross-section, but the latter is preferably selected according to the containers to be treated.

The machine illustrated in Figs. 2, 3 and 4 is specially designed for products wherein intense agitation is preferable during treatment. It comprises two tanks 24 and 25, one for cold and the other for hot water. In said tanks there are respectively arranged endless circulating runways 26 and 26a along which the baskets 23 are made to circulate in self-rotation by being pushed along by the fingers 1 and 1a of endless chains 2 and 2a driven by wheels 4 and 4a mounted on shafts 5 and 5a. The total number of fingers in each chain is suitably determined according to requirements.

Pairs of star-shaped wheels 6-7 and 6a-7a, synchronously rotated with the displacement of the endless chains 2, 2a, respectively provide for introducing baskets 23 into, and removing same from, the endless circuits 26 and 26a guiding said baskets in the tanks. The wheels of each pair mounted on parallel axes and rotated in the same direction, are disposed opposite one another and are separated by a partition 27 or 27a having a suitable section and shape for laterally maintaining baskets 23 within the corresponding notches of the star-shaped wheels. The number of notches in said star-shaped wheels, and the number of fingers in the endless chains, are chosen in any suitable way in relation with the operation of extracting arms 8 and 8a, actuated for instance by cams not shown but familiar in the art, operated synchronously with the displacement of the endless chains 2 and 2a and the star-shaped wheels, in such a way that the baskets will be extracted from the runways 26 and 26a after having sojourned for a suitable period of time in the tanks. Thus, for example, there will be 25 fingers on each of the endless chains 2, each wheels 6, 6a, 7 and 7a comprising 8 notches.

A conveyor arranged at the upper part of the tanks and constituted by two lateral runways 28 each having an endless chain 29 provided with fingers 30 similar to fingers 1, ensures the transfer of the baskets from one tank to another in co-operation with the star-shaped wheels placed in said tanks. Moreover, and according to an important feature of the present invention, a shelved, or downwardly offset, portion 31 is provided in the runway 28 for allowing the baskets to remain stationary for a certain time so as to enable them to be filled and drawn off with greater ease.

Operation of the device is as follows:

At X and Y, two baskets at least are in stationary condition, at X the treated containers are extracted from the basket 23a, and at Y the containers to be treated are inserted into the

basket 23b. An arm 9, actuated by any suitable means synchronously with the displacement of the endless chains 29 introduces the basket 23c into the conveyor formed by said chains 29 and the guideways 28 at regularly spaced intervals so as to introduce one basket after the passing of each group of eight fingers 30. This basket 23 is introduced, by the star-shaped wheel 6, into the hot water tank 25, and travels several times around its circuit until it is again introduced into the upper conveyor, by the arm 8 and the star-shaped wheel 7. According to the adjustment of the arm 8, the basket 23 may travel as many as eight times around the circuit provided in the tank 25. The basket then passes into the circuit of tank 24, according to the same principles of operation, and emerges by means of the star-shaped wheel 7a by which it is conveyed into extracting position as shown at X (see also Fig 8).

It is obvious that the tank circuits which have been shown in the drawing as comprising two stages may include three or four stages or more. The number of fingers 1 and chains 2 and the number of notches in wheels 6 and 7 will be selected according to requirements. Similarly, instead of the pair of tanks illustrated there could be a plurality of tanks, at stepped temperatures, as described hereinafter with reference to Fig. 11.

The machine which is diagrammatically shown in section in Fig. 9 is more particularly designed for the treatment of containers by means of steam under pressure. For this purpose, the actual treatment is carried out in a sealed enclosure 33 filled with steam. Said enclosure 33 comprises at its lower portion a fluid tight partition 34 defining a space 35 connecting through a tunnel 36 with a chamber 37 divided in two columns at the upper portion thereof by a partition 38. Said chamber 37 is filled with water up to a level which is adjusted as a function of the steam pressure which it is desired to maintain in the treating enclosure 33. The guideways 39 for baskets 23 which form the continuous circulating circuit for said baskets 23 pass into enclosure 33 and chamber 37, and the chains 40 provided with driving fingers 41 pass around counter-motion pulleys 42 suitably arranged so that said chains 40 will extend along the path of the guideways 39 substantially throughout the whole length of said guideways. Baskets 23 filled with containers to be treated enter at P the water-filled chamber 37, then arrive in the treating enclosure 33, pass out of the latter to again enter chamber 37, whence they again emerge at Q. Cold water is admitted at 43, is heated by contact with the baskets 23 fed through the enclosure 33, and is evacuated at 44, a constant level being maintained in chamber 37 at the desired height depending on the steam pressure within enclosure 33. Said steam is admitted through a suitable valve (not shown) controlled by a float 45 in such a way as to maintain a constant pressure of steam within enclosure 33.

Outside enclosure 33 and chamber 37, there is provided at 45a a displacement of the guideway with respect to the drive chains 40 in order to obtain a stationary condition of baskets 23 during a certain period of time enabling such baskets to be filled and drawn off respectively in position X and Y thereof. An arm 46, controlled by a cam 47 or an equivalent device driven synchronously with the driving chains 40, provides for extracting the baskets from said drive chains 75 and transfers them to the offset portion 45 of

the guideways whereas they are emptied and then filled before again being engaged at 48 by the driving fingers 41 of said chains.

More particularly in the event where the bottoms of metallic cans are liable to be puffed, or expand, during treatment and in order to avoid damage to such cans and to the baskets in which they are contained by reason of such increase in volume, a device may be provided adapted to reserve within the basket a certain space remaining empty of cans. In one form of embodiment which appears advantageous at present, such device consists of a finger 49 which, as the basket is filled, is caused to extend into the end of said basket opposite to that at which said basket is filled to the desired extent. Said finger 49 is actuated by any suitable means and for example by levers (not shown) driven from the cam 47 actuating the arm 46.

The machine diagrammatically illustrated in Fig. 10 is more particularly designed for treating containers in hot water, which may be subject to an excess pressure. For that purpose, the treating chamber 50 filled with hot water opens at its upper portion in an enclosure comprising a pair of columns 51 and 52 forming a U. Column 51 is filled with a mixture of air and vapour, while column 52, open at its upper end, contains water, the upper level of which with respect to the level of water in the branch 51 determines the degree of excess pressure which it is desired to apply to the hot water contained in the treating chamber 50. Circulating runways 53 with their chains and fingers for driving baskets 23 similar to those described in the preceding devices are provided for within chamber 50 and columns 51 and 52, and said runways 53 also comprise an offset portion and an extractor arm for the baskets as in the example of Fig. 5, so as to ensure a stationary condition of the baskets for a certain length of time for loading and unloading purposes.

In the machine diagrammatically shown in Fig. 11, baskets 23 are circulated by means of guiding and driving devices similar to those described in the other embodiments, within tanks or chambers 60, 61 and 62 filled with a heated fluid, the temperatures of which are so adjusted that the containers to be treated will progressively pass from the temperature at which they have been filled to the maximum temperature of the fluid contained in the tank 60, and vice-versa, the displacement of the endless chains driving the baskets being in the direction of arrows f_1 . This type of installation is particularly suitable for the treating of brittle containers such as glass containers, for instance for the pasteurizing of beer, fruit juice and the like.

In 61 and 62, the water transfers the heat calories from the treated containers to those to be treated, thus providing in the simplest possible manner for the gradual progression of the temperatures and a saving in the heating steam and cooling water.

The tanks may, of course, be provided in any desired number.

In all the devices described hereinbefore, adjusting means for regulating the rate of displacement of the endless drive chains are provided for so as to carry out the desired appropriate treatment in optimum conditions.

Figs. 13 to 16 show diagrammatically and by way of example, one form of embodiment of a mechanical device which may be used for filling containers to be treated into the baskets, and

also for ejecting said containers at the end of the treatment, during the stationary period of the baskets.

This device essentially consists of a plunger 70, the shape and dimensions of which correspond to the interior of the baskets. Said plunger 70 is slidably mounted in a guide-member 71, the open end of which is positioned in register with a basket 23 which is in stationary position at x or y (Fig. 8). The plunger 70 is reciprocally driven by an arm 75 pivotally mounted on a pin 75a carried by the plunger 70, said arm being connected by a finger 82 to a chain 72 the path of which is contained in a plane perpendicular to the vertical planes containing the chains 29 and which is trained over a pair of spaced sprockets 73 and 74, at least one of which is power driven by any appropriate means in such a way that plunger 70 is reciprocated in guide 71 and engages the inside of the basket 23 which is in register therewith. Owing to such an engagement, the plunger 70 which is in register relationship with basket 23a, stationary at X (Figs. 2 and 8) discharges the containers filling said basket 23a by forcing them out said basket, while the plunger 70 which is in register relationship with basket 23b (Figs. 2 and 8) may charge said basket 23b with containers to be treated. In the latter case, the guide 71 (Fig. 15) is formed with an aperture 80 at its top through which pass the containers which are to be introduced into said basket 23b while the corresponding plunger 70 is at its rearmost position.

In the event the containers to be extracted from the baskets are brittle, as for instance made of glass, plunger 70 is provided with a trough or scoop 3 (Figs. 16 and 17) of appropriate shape which is introduced into the basket at the bottom thereof under said containers, to thereafter carry said containers out of said basket. The containers may be cleared, or disengaged, from said trough or channel arm by any suitable means and for example by a partial upsetting of said trough at the end of its stroke. Such upsetting could be produced by a lug integral with the trough and movable within an aperture of suitable contour formed in the guide of said trough. A similar device may be provided for loading the containers into the baskets.

What I claim as my invention and desire to secure by Letters Patent is:

1. The combination with an apparatus for thermal treatment of stuffs in containers and of the type comprising an enclosure containing a thermal treating fluid, at least a pair of two continuously driven chains respectively arranged in parallel closed circuits positioned in vertical planes within the enclosure and pushing members distributed upon said chains, of tubular baskets open at each end, adapted to receive containers and having a length slightly less than the distance existing between the parallel chains and a diameter less than the distance existing between two successive pushing members of the chains, a pair of guiding tracks respectively co-extensive with each pair of parallel chains and positioned with respect to said chains at a distance slightly larger than the outer radius of said tubular baskets, said baskets being respectively guided by the two tracks of each pair of chains between two successive pairs of pushing members and being unattached to said chains, said guiding tracks being further formed with respect to one of the closed circuits with a pair

of facing offset portions departing from said chains and forming an offset place, means for successively and periodically extracting at least one of said baskets from said last closed circuit and for conveying the same to said offset place, each extracted basket remaining motionless in said place between two successive extractions, whereby each extracted basket may be discharged and charged at said offset place during predetermined stopping periods without being taken out of the treating apparatus, and means for reintroducing said extracted baskets when charged into said last closed circuit.

2. An apparatus for the thermal treatment of stuffs in containers, according to claim 1, wherein the means for extracting the basket from the closed circuit comprises a rotary member formed with at least a radial projection adapted to extract one basket from the closed circuit corresponding to the offset place and means for rotatably driving said member in synchronized relationship with the motion of the parallel chains.

3. An apparatus for the thermal treatment of stuffs in containers, according to claim 1, further comprising means for removing the containers from each basket in predetermined stationary position in the offset place and for charging the same with containers, said means respectively having a plunger reciprocably movable along the axis of the stationary basket for penetrating within said basket, an auxiliary endless chain arranged in closed circuit positioned in a vertical plane perpendicular to the vertical plane containing the parallel chains, and a finger fixedly mounted on said auxiliary chain and connected with said plunger.

4. An apparatus for the thermal treatment of stuffs in containers, according to claim 1, further comprising, in the case where the containers are glass containers, means for removing said containers from each basket in predetermined stationary position in the offset place and for charging the same with containers, said means respectively having a plunger reciprocably movable along the axis of the stationary basket for penetrating within said basket, and auxiliary endless chain arranged in closed circuit positioned in a plane perpendicular to the vertical planes containing the parallel chains, and a finger fixedly mounted on said auxiliary chain and connected with said plunger, said plunger being provided with a scoop directed toward said basket and of appropriate shape for passing first below the containers all along the basket and then conveying them out of the basket with a view to avoid any risk of jamming in the case any container is broken.

5. In an apparatus for the thermal treatment of stuffs in containers, at least two enclosures containing the thermal treating fluids, within each of said enclosures two treating endless conveyor chains arranged in two closed circuits positioned in vertical planes on each side of the corresponding enclosure, series of regularly spaced opposite fingers fixedly mounted on said chains and projecting between said vertical planes and two runways substantially co-extensive with said conveyor chains, tubular baskets unattached to the chains, filled with containers, provided with outwardly cylindrical end members lying upon said runways and located between two successive fingers of each of said chains for being propelled along said runways by the pushing action of said fingers against said cylindrical end members, and

an interconnecting assembly for connecting together said various closed circuits located within said enclosures and comprising two common endless conveyor chains similar to said treating conveyor chains and provided with fingers similar to those of said treating conveyor chains, said common conveyor chains being arranged in vertical common closed circuits located above said various treating conveyor chains, two runways substantially co-extensive with said common conveyor chains throughout a major portion thereof and provided with respect to the lower flights thereof with an offset portion, star-shaped rotary members for transferring the baskets from said common conveyor chains to each of said treating conveyor chains and reciprocally, means for successively periodically extracting said baskets one by one from said common closed circuits and for conveying the same on said offset portion, each extracted basket remaining motionless on said offset portion between two successive extractions and being displaced when an extraction occurs by contact with the following extracted basket, whereby each extracted basket may be discharged and charged at said offset place during predetermined stopping periods without being taken out of the treating apparatus, and means for reintroducing one by one said extracted baskets when charged into said common closed circuits.

6. An apparatus for the thermal treatment of stuffs in containers, according to claim 5, comprising means for causing several travels of the basket around each treating closed circuit before being transferred by the corresponding star-shaped rotary member to the common conveyor chain.

7. An apparatus for the thermal treatment of stuffs in containers, according to claim 6, wherein in the number of notches in the star-shaped rotary members is a prime number with respect to the number of fingers in the treating endless conveyor chains.

8. In an apparatus for the thermal treatment of stuffs in containers by means of steam under pressure, an enclosure containing steam under pressure and sealed at its upper part, two successive pressure columns containing a liquid and connected with the lower part of said enclosure, two endless conveyor chains arranged in two closed circuits travelling successively within the first pressure column, said enclosure and the second pressure column, said closed circuits being positioned in spaced parallel vertical planes, series of regularly spaced opposite fingers fixedly mounted on said chains and projecting between said vertical planes, two runways substantially co-extensive with said conveyor chains throughout a major portion thereof and provided with respect to a portion of said chains with an offset portion, tubular baskets unattached to said chains, filled with containers, provided with outwardly cylindrical end members guided by said runways and located between two successive fingers of each of said chains for being propelled along said runways by the pushing action of said fingers against said cylindrical end members, means for successively periodically extracting at least one of said baskets from said closed circuits and for conveying the same on said offset portion, each extracted basket remaining motionless on said offset portion between two successive extractions, whereby each extracted basket may be discharged and charged at said offset place during predetermined stopping

periods without being taken out of the treating apparatus, and means for reintroducing said extracted baskets when charged into said closed circuits.

9. An apparatus for the thermal treatment of stuffs in containers by means of steam under pressure, according to claim 8, comprising means for continuously and adjustably introducing the liquid in the upper part of the second pressure column and means for discharging said liquid from the upper part of the first pressure column.

10. In an apparatus for the thermal treatment of stuffs in containers by means of a hot liquid subjected to an excess pressure, an enclosure containing hot liquid and sealed at its lower part, an intermediate chamber containing inactive gas and connected at its upper part with the upper part of said enclosure, two successive water pressure columns, two endless conveyor chains arranged in two closed circuits travelling successively within the first pressure column, said intermediate chamber, said enclosure, said intermediate chamber anew and the second pressure column, said closed circuits being positioned in spaced parallel vertical planes, series of regularly spaced opposite fingers fixedly mounted on said chains and projecting between said vertical planes, two runways substantially co-extensive with said conveyor chains throughout a major portion thereof and provided with respect to a portion of said chains with an offset portion, tubular baskets unattached to said chains, filled with containers, provided with outwardly cylindrical end members guided by said runways and located between two successive fingers of each of said chains for being propelled along said runways by the pushing action of said fingers against said cylindrical end members, means for successively periodically extracting at least one of said baskets from said closed circuits and for conveying the same on said offset portion, each extracted basket remaining motionless on said offset portion between two successive extractions, whereby each extracted basket may be discharged and charged at said offset place during predetermined stopping periods without being taken out of the treating apparatus, and means for reintroducing said extracted baskets when charged into said closed circuits.

11. In an apparatus for the thermal treatment

of stuffs in containers, more particularly in glass containers, a plurality of successive enclosures containing thermal treating fluid the temperature of which increases gradually from one enclosure to the adjacent one, two endless conveyor chains arranged in two closed circuits travelling successively within said successive enclosures, said closed circuits being positioned in spaced parallel vertical planes, series of regularly spaced opposite fingers fixedly mounted on said chains and projecting between said vertical planes, two runways substantially co-extensive with said conveyor chains throughout a major portion thereof, and provided with respect to a portion of said chains with an offset portion, tubular baskets unattached to said chains, filled with containers, provided with outwardly cylindrical end members guided by said runways and located between two successive fingers of each of said chains for being propelled along said runways by the pushing action of said fingers against said cylindrical end members, means for successively and periodically extracting at least one of said baskets from said closed circuits and for conveying the same on said offset portion, each extracted basket remaining motionless on said offset portion between two successive extractions, whereby each extracted basket may be discharged and charged at said offset place during predetermined stopping periods without being taken out of the treating apparatus, and means for reintroducing said extracted baskets when charged into said closed circuits.
